UNITED STATES PATENT OFFICE.

DAVID A. McDONALD, OF CHICAGO, ILLINOIS, ASSIGNOR TO LYON & HEALY, OF CHICAGO, ILLINOIS, A CORPORATION OF ILLINOIS.

TROMBONE.

1,263,085.

Specification of Letters Patent. Patented Apr. 16, 1918.

Application filed February 19, 1917. Serial No. 149,383.

To all whom it may concern:

Be it known that I, DAVID A. McDONALD, a citizen of the United States of America, and resident of Chicago, Cook county, Illinois, have invented a certain new and useful Improvement in Trombones, of which the following is a specification.

My invention relates to an improvement in trombones, and particularly to an improved construction in the slide, whereby this slide may be readily moved to its various playing positions. The feature of my invention consists in providing a novel construction by which the ready movement of this slide is greatly facilitated in that the area of frictional engagement between the telescoping members is greatly decreased without, at the same time, unnecessarily decreasing the length of the bearing surface. In this manner, I am enabled to provide an efficient and firm bearing between the two parts of the slide and yet so decrease the area of frictional engagement as to render the slide more easy of operation. These and other features and objects of my invention will be more readily understood by having reference to the accompanying drawings, in which I have illustrated one form of trombone embodying the features of my invention.

Figure 1 is a side elevation of a trombone constructed in accordance with my invention.

Fig. 2 is an enlarged detail view of a portion of the slide bearing.

Fig. 3 is a sectional view taken on the line 3—3 of Fig. 2.

Fig. 4 is a detail view of one arm of the slide bearing, showing a modified construction.

As illustrated, I have shown a trombone of well known type comprising the bell 5, mouth-piece 6 between which is located the usual tone slide consisting of the U-member 7 which telescopes over the two parallel arms 8 and 9. This U slide is provided with the usual cross piece 10 whereby it can be moved in and out to its various playing positions.

In previous constructions it has been found that, owing to the large area of surface engagement between the U slide 7 and the arms 8 and 9, there is a tendency for the slide to stick and that therefore it is difficult to quickly and accurately move the slide to

the desired position while playing the instrument. In order to avoid such objectionable features, and to provide a slide which not only is firmly mounted on the arms 8 and 9 but also one which can be readily slid in and out over such arms I provide a novel construction, clearly shown in Fig. 2. This consists of a bearing ring or stocking 11 which is mounted on the end of each of the arms 8 and 9, which bearing ring is comparatively short but forms a close air tight connection between the two members. By having this bearing member constructed comparatively short in this manner, I avoid unnecessary friction between the telescoping members. However, if such a short bearing member were used alone it would not be sufficient to hold the U slide firmly on the arm—that is, the U slide would tend to wobble and not be firmly held when the slide was drawn out to its lower positions. In such a construction, the slide not being held in proper alignment, there is a tendency for this slide to jam when being moved quickly from one position to another, and in this way interferes with the free movement of the slide. In order to obviate this objectionable feature I provide a plurality of bearing strips 12 which are secured to the surface of the arms 8 and 9 adjacent to the bearing rings. These strips are of sufficient length to provide a firm bearing between the telescoping members and are placed circumferentially around the tubular arms with a space between the same. In this manner I have provided an elongated bearing surface with a minimum area of surface engagement between the telescoping parts and thus obtain this increased length of engagement without materially increasing the friction between the parts.

In Fig. 4 I have shown a slightly modified construction in which instead of having the bearing ring and bearing strips formed separately I provide a single bearing member which is mounted on the end of the arms 8 and 9, this member consisting of a metallic collar 13 to which are secured the elongated arms 14, intermediate spaces 15 being provided between each pair of arms. In this construction, as in the previous construction, it will be noticed that I have provided a maximum length of bearing surface whereby the U slide is firmly supported on the tubular arms without unduly increasing the

total surface engagement between the members and thus without unduly increasing the friction between the telescoping parts.

It will thus be seen that I have devised a very efficient structure and one in which the U-slide is firmly and efficiently supported on the tubular arms of the instrument and in such a manner that the frictional engagement between the moving parts is reduced.

10 It will be noticed that in the construction shown in Fig. 2 there is a small space between the inner end of these bearing strips and the bearing rings 11. This is of utility in cleaning the instrument from dust or

15 other foreign particles.

While I have illustrated and described certain specific constructions for carrying out the features of my invention, it will be understood that other forms may suggest them-

20 selves to those skilled in the art without departing from the spirit and scope of my invention.

What I claim as my invention is:

1. A trombone comprising a pair of parallel tubular arms, a U-slide in telescoping engagement with said arms, and a plurality of bearing strips secured to said tubular arm and forming a bearing between said arms and said slide.

2. A trombone comprising a pair of parallel tubular arms, a U-slide in telescoping engagement with said arms, and a bearing ring and a plurality of elongated bearing strips on each of said arms for forming a bearing between said arm and said U slide.

30 35 Signed by me at Chicago, Illinois, this 14 day of February, 1917.

DAVID A. McDONALD.
